FIG. 2.

UNITED STATES PATENT OFFICE

ELMER B. FENTON AND WILBUR C. FENTON, OF CEDAR RAPIDS, IOWA

CURTAIN STRETCHER

Application filed February 21, 1929. Serial No. 341,732.

This invention relates to stretching frames and pertains particularly to an improved type of frame for stretching curtains, particularly lace curtains.

5 The primary object of the present invention is to provide a lace curtain stretching frame designed for stretching all types of curtains but having associated therewith a means for engaging the scalloped lower edge 10 of those curtains having fringe depending therefrom.

Another object of the invention is to provide a curtain stretching frame of such construction that it may be enlarged laterally 15 and longitudinally after a curtain has been placed thereon for drawing the curtain tight.

A still further object of the invention is to provide a frame structure for stretching curtains which may be employed for stretching 20 several curtains at one operation, even though the curtains may be of different lengths.

Still another object of the invention is to provide a curtain stretching frame which may 25 be so disassembled as to permit it to be reduced to a relatively small size to facilitate storing.

The invention will be best understood from a consideration of the following detailed description taken in connection with the accompanying drawing forming a part of this specification, with the understanding, however, that the invention is not confined to any strict conformity with the showing of 30 the drawing but may be changed or modified so long as such changes or modifications mark no material departure from the salient features of the invention as expressed in the appended claims.

40 In the drawing:—

Figure 1 is a view in front elevation of the curtain stretcher embodying the present invention;

45 Figure 2 is a side elevational view of the stretcher;

Figure 3 is a sectional view taken upon the line 3—3 of Figure 1;

50 Figure 4 is a sectional view taken on the line 4—4 of Figure 1;

Figure 5 is a sectional view taken upon the line 5—5 of Figure 1;

Figure 6 is an enlarged detailed view of one end of the bar designed for holding the scalloped edge of a curtain.

Referring to the drawing in detail, the numerals 1 each indicate generally the side members or bars of the frame embodying this invention, which members are designed to be arranged in substantially upright position when the frame is set up. As shown, each of these members is formed in upper and lower sections 2 and 3, respectively, which are connected and held in alignment by the turnbuckles 4, by means of which they may be longitudinally adjusted relative to one another.

The side members 1 of the frame are joined together by the transverse upper and lower connecting bars, indicated generally by the numerals 5 and 6, respectively, each of these bars being formed in two sections, each of which is indicated by the numeral 7, the sections being arranged in end aligned relation and threadably connected by turnbuckles 8. The ends of the cross connecting bars 5 and 6 are secured in any appropriate manner to the adjacent members of the side bars 1 and each is braced adjacent its point of connection with a side bar by the angularly directed brace members 9.

Each of the side bars 1 has secured thereto the forwardly and laterally directed members 10 to which the edges of a curtain may be secured. To the upper end of each of the portions 2 of each side bar there is secured a plurality of forwardly and upwardly directed supporting hooks 11 and secured to the lower ends of each of the portions 3 of the side members or bars are similar but downwardly directed hooks 12. To the back of the upper portion of each of the side bars 1 is secured a hinge eye 13 through which is pivotally engaged the yoke portion 14 of an inverted substantially U-shaped prop frame 15, each of the legs of the frame being adjustably connected to the adjacent side bar of the curtain stretching frame by a chain 16.

Connecting the upper ends of the side bars

1 and resting upon the hooks 11 are curtain supporting bars 17 and designed for use in association with the lower hooks 12 for engagement thereunder and for holding down the lower ends of curtains secured to the frame are similar transversely extending bars 18.

With the structure thus far described it will be readily seen that curtains having 10 hems across the upper and lower edges may be readily mounted upon this frame by engaging the side edges thereof over the hooks 10 of the side bars and by running one of the upper bars 17 through the top hem and supporting it upon the hooks 11 and extending one of the lower bars 18 through the lower hem and drawing it to position for engagement beneath the hooks 12. The curtain will then be held tightly across the frame.

20 In order to adapt the frame to curtains having scalloped lower edges to hold the scalloped portions tight while the curtain is drying, there is provided the structure indicated as a whole by the numeral 19. This 25 structure comprises a pair of transverse bar members 20 which are arranged in spaced parallel relation and which have secured thereto the transversely extending bar 21 of sinuous design. The loops or folds of this 30 bar 21 extend in a substantially vertical plane with the frame and are set up for use and designed to substantially conform to the curves of the scalloped edge of the curtain. This bar, like the side bars 1 carries a plurality of outwardly and downwardly projecting hooks 22 with which the lower scalloped edge of the curtain is adapted to engage.

35 The structure at 19 is held in position in substantially the same manner as the lower one of the bars 18, that is, by stretching the curtains downwardly after the hooks are engaged therewith, until one of the bar members 20 thereof can be engaged at its ends beneath the downwardly extending hooks 12.

40 In order to hold the bars 18 in position while securing the edges of a curtain to the frame or in order to hold one of the bars 18 in position while the other is being attached 45 to the curtain, there is provided in association with each of the pins or hooks 11 a stud 23, each stud being so spaced from the adjacent pin that a bar may be frictionally engaged between it and the pin, as clearly 55 shown in Figure 5.

As is shown in Figure 6, these studs also act to hold one of the bars 20 of the structure 19 in place while the curtain is being attached thereto.

50 In Figure 4 there is shown a portion of a curtain indicated by the numeral 24 having a fringe 25, showing the manner in which the hooks 22 of the structure 19 engage the hem adjacent the fringe.

55 From the foregoing description it will be

readily seen that a number of curtains may be readily placed upon the stretching and drying frame and that curtains having scalloped edges may be stretched right to the edge of the scalloped portion instead of from a point inwardly of the scallops as they would be if applied to the usual stretching frame where the bottom row of pins for engaging the curtain extend straight across the frame.

70 While no particular material has been referred to for constructing a frame of this sort, the same has been shown as constructed of metal and this material when suitably treated to prevent rusting is preferable to others, however, it is to be understood that we do not wish to be limited to the use of this material for it is obvious that with slight 75 alterations a wooden frame may be readily employed without departing from the spirit of the present invention, as expressed in the 80 claims.

Having described our invention, what we claim is:—

1. A curtain stretching and drying device comprising a frame consisting of a pair of substantially parallel side bars, connecting members between said side bars inwardly of the ends thereof, means whereby said side bars may be lengthened or shortened, means whereby the side bars may be shifted relative 90 to one another, curtain edge engaging members connecting said side bars adjacent their ends, and means forming a part of one of said curtain edge engaging members whereby a scalloped edge of a curtain may be engaged throughout its length for stretching the scalloped portions said scalloped edge engaging means comprising a plurality of spaced transverse bars and a sinuous member mounted 95 thereon.

100 2. A curtain stretching and drying device comprising a frame consisting of a pair of substantially parallel side bars, connecting members between said side bars inwardly of the ends thereof, means whereby said side bars may be lengthened or shortened, means whereby the side bars may be shifted relative 105 to one another, curtain edge engaging members connecting said side bars adjacent their ends, and means forming a part of one of said curtain edge engaging members whereby a scalloped edge of a curtain may be engaged throughout its length for stretching the scalloped portions, said means comprising a pair 110 of transverse bars and a sinuous member having the curves thereof adapted to be positioned in a substantially vertical plane, said curves substantially conforming to the scallop of a curtain edge, and hook members carried by the sinuous bar.

115 In testimony whereof we hereunto affix our signatures.

ELMER B. FENTON.
WILBUR C. FENTON.
